UNITED STATES PATENT OFFICE

1,928,800

ABRASIVE APPARATUS

William Stever, Philadelphia, Pa., assignor to The Stratmore Company, Cleveland, Ohio, a corporation of Ohio

Application June 14, 1929. Serial No. 370,904

1 Claim. (Cl. 51—197)

The present invention, relating, as indicated, to abrasive apparatus, is particularly directed to a new and improved supporting pad for an abrasive disk employed in the now common types 5 of portable abrasive or surfacing machines. These machines, which are in common use for the surfacing of panels, etc., consist of a casing provided with handles for the operator and containing either an electrical or pneumatic motor 10 or driving gears which receive power from a flexible shaft. The casing also supports an extending shaft, on which is mounted, first, a yieldable pad of some construction, and then against the outer surface of the pad, an abrasive disk, the 15 pad and disk being secured to the shaft at their respective centers and being ordinarily otherwise free from each other.

These machines have gone into very extensive use and are employed with various sizes of abrasive disks, such as 9", 7", 5", etc. with various 20 individual pads of the proper size supporting each size of disk. As the disks are applied to the work at their outer surfaces, this is the part which first wears away and the disks are then 25 sometimes cut down to the next size and must then of course be used with a different size of supporting pad.

The object of the present invention is the provision of a yieldable supporting pad constructed 30 to permit of work with the edge of the abrasive disk and formed of separable units to allow the same pad to be successively used with various sizes of disks upon removal of one or more of the separable parts of this supporting element. 35 A further object of the invention is the provision of a simple and very inexpensive pad of this type suitable for certain types of work and permitting both use of the disk on its flat portion and also at its edge to surface concave surfaces, 40 such for example as those which occur between a metal panel and a superimposed molding strip.

To the accomplishment of the foregoing and related ends, said invention, then, consists of the means hereinafter fully described and particularly 45 pointed out in the claim; the annexed drawings and the following description setting forth in detail certain structure embodying the invention, such disclosed means constituting, however, but one of various forms in which the principle 50 of the invention may be used.

In said annexed drawings:—

Fig. 1 is a plan view of my improved pad and supporting hub therefor; Fig. 2 is a transverse section on the plane 2—2, Fig. 1; Fig. 3 is a bottom plan view of the hub; Fig. 4 is a section

on the line 4—4, Fig. 3; Fig. 5 is a plan view of the largest of the separable elements of the pad; Fig. 6 is a view similar to Fig. 2, but showing the pad with its largest element removed; and Fig. 7 is a transverse sectional view showing the 60 pad and disk supported thereby in use against a concave surface.

Referring now to Figs. 1 and 4, inclusive, there is shown a hub 1 provided with a central threaded opening 2 adapted to be engaged upon a corresponding threaded end of the supporting shaft of a portable machine such as I have described. This hub 1 is provided with a central locating projection 4 and with two oppositely directed 65 engaging wings 5, each of which consists of a portion 6 which extends angularly from the lower face of the hub 1 and a second portion 7 which extends almost parallel with the surface of the hub 1. The central locating projection 4 and the wings 5 serve to engage and hold in proper 70 registration the separable elements which comprise my improved supporting pad and also the abrasive disk supported thereby.

The separable elements of my pad consists of 75 disks 10, 11 and 12 shown in Fig. 2, which may 80 be formed of some tough resistant material, such as vulcanized fiber. Each of these disks is of some thickness and is provided at a central portion with a central opening 13 and connecting 85 slots 14 and 15. The opening 13 engages over the locating projection 4 on the hub and the slots 14 and 15 engage over the portions 7 of the wings 5 and are then brought into engagement with the portion 6 of these same wings by being given a 90 slight rotational movement about the hub. An abrasive disk 20, provided with a similar central opening and connecting slots, is then similarly engaged over the projection 4 and the rings 5 and is rotated in a snug frictional engagement beneath the lower tapered surfaces of the portions 95 6 and 7 of the wings 5.

When it is desired to use a disk of smaller size the large disk 20 is removed by being turned in a direction to cause the slots to ride up over the wings 5, after which the larger element 10 is similarly removed. A disk of the same size as the 100 second of the supporting elements 11 is then applied in the same manner as before.

If a disk of the smallest size is to be used, then 105 both the elements 10 and 11 are removed and the disk is applied over the supporting element 12. In this way the supporting pad may be quickly and conveniently adapted for use with any one of a series of selected disk sizes, and while the 110 supporting element is of less thickness and resist-

ance as its size is decreased by the removal of the larger disks, this decrease in resistance makes very little difference as the necessity for support decreases with the size of the disk and with the amount which the disk overhangs the central supporting hub 1.

My supporting pad is particularly intended for such operations as are shown in Fig. 7, in which a disk 25 is supported by the two elements 11 and 12 of the supporting pad and is employed against a concave surface 26. The outer edge only of the disk is in effective operation and the nature of the supporting pad is such that this edge can be used to enter sharply concave recesses, such as are shown between a panel 27 proper and a bead strip 28.

The present pad may also be used for supporting abrasive disks in the more common operations, such as surfacing flat panels, where a considerable area of the disk engages the panel and I have found that the separable supporting elements, if formed of a tough resistant material, are an entirely adequate support for disks for most of their operations, are relatively inexpensive and have a relatively long life.

It will be understood that while I have shown special engaging means for maintaining the sep-

arable parts of the supporting pad and the disk in operative relation, other means may be employed for this purpose, such for example as a standard flat headed screw which is employed in most machines of this character for clamping the surfacing disk against the supporting pad.

Other modes of applying the principle of my invention may be employed instead of the one explained, change being made as regards the structure herein disclosed, provided the means stated by the following claim or the equivalent of such stated means be employed.

I therefore particularly point out and distinctly claim as my invention:—

A supporting element of the character described comprising a rigid hub provided with oppositely directed circumferentially extending locking wings on one surface, a series of stepped separable supporting disks removably engaging concentrically upon said locking wings, an abrasive disk substantially coextensive with the largest of said supporting disks also removably locking upon said wings, each of said disks being separately removable to leave the next smaller disk adjacent said abrasive disk.
